(57) **CLAIM**

The ornamental design for a foam holder for items, as shown and described.

DESCRIPTION

FIG. 1 is a top perspective view of a foam holder for items, showing my new design;
 FIG. 2 is a top plan view thereof;
 FIG. 3 is a bottom plan view thereof;
 FIG. 4 is a front elevational view thereof, the rear elevational view being a mirror image thereof; and,
 FIG. 5 is a left-side elevational view thereof, the right-side elevational view being a mirror image thereof.
